UNITED STATES PATENT OFFICE.

CHAUNCEY L. OLMSTEAD, OF BROOKLYN, NEW YORK.

IMPROVEMENT IN APPARATUS FOR CLASPING HOOP-SKIRTS.

Specification forming part of Letters Patent No. 50,728, dated October 31, 1865.

To all whom it may concern:

Be it known that I, CHAUNCEY L. OLMSTEAD, of Brooklyn, in the county of Kings and State of New York, have invented certain new and useful Improvements in Apparatus for Clasping Hoops to Hoop-Skirts and similar Articles; and I do hereby declare that the following is a full, clear, and exact description of my said invention, reference being had to the accompanying drawings, in which—

Figure 1 represents a vertical longitudinal section of a part of a hoop-clasping machine with my improvements applied thereto. Fig. 2 represents a top view of a part of the machine, looked at in the direction of the arrow *a*, Fig. 1; and Fig. 3 represents a transverse section of a part of the machine at the line *xx* of Fig. 2, seen in the direction of the arrow *b*.

My improvements relate to the feed mechanism of hoop-clasping machines. In such machines the clasps are placed promiscuously in a slightly-inclined pan-hopper, from which the jar of the machine causes them to escape and pass to the upper end of an inclined feeding-plate, down which they slide to the clasp-supplying device, which holds them in line and supplies them in succession to the clasping mechanism. During the passage of the clasps down the inclined feeding-plate they come in contact with inclined directing-bars, whose function is to cause the clasps to arrange themselves, with their tongues, in the proper positions they are to occupy in order to be received into the clasp-supplying device. The operation of such bars has been found by experience to be inadequate to the requirements of the machine, and, besides, many clasps which do not attain their proper positions pass over the entrance of the feed-supplying device and are scattered on the floor, thus occasioning material loss.

The object of my improvements is to render the delivery of the clasps to the clasp-supplying device more certain and to lessen the loss of clasps.

To this end the first part of my improvement consists of the combination of the feeding-plate with what I term a "needle," consisting of a thin pointed rod secured to the feeding-plate in advance of the passage to the feed-supplying device, with its point extending toward

the clasp-hopper, so as to act upon the clasps as they descend and permit such only as have attained the requisite position to pass into the feed-supplying device.

The second part of my invention consists of the combination of the feeding-plate with a gate placed in the passage to the feed-supplying device, and having an opening in it to permit the clasps which have been properly arranged to escape one at a time, but closing the remainder of the passage in such manner as to prevent the escape of misarranged clasps and insure their delivery through an opening communicating with a receptacle in which they are caught.

As the construction, arrangement, and mode of operation of machines for clasping hoops to hoop-skirts are well understood, I do not deem it necessary to represent and describe a complete machine, but I have represented in my drawings all the parts of the machine to which my invention appertains. The remaining parts of the machine may be constructed as described in the Patent No. 37,124, granted to Jedediah Wilcox, assignee of Joseph H. Baird, the 9th day of December, 1862.

The hopper *A* of the machine consists of a shallow pan, slightly inclined and having an opening, *d*, at its lowest part, from which the clasps escape by the jar of the machine and pass to the feeding-plate *B*. The feeding-plate is inclined in the usual manner. It is fitted at one side with a bar, *C*, which prevents the escape of clasps, and at the other with an inclined guide-bar, *D*, having a groove or opening at its lower side to admit the flanges of the clasp, and so located in respect to the opening of the hopper from which the clasps escape that they come in contact with it, and by sliding down in such contact are caused to arrange themselves with their tongues in proper positions to enter the clasp-supplying device *E*. The side bar, *C*, and guide-bar *D* converge, so that their lower ends form a narrow passage through which the clasps pass to the entrance of the clasp-supplying device. The needle *m* is arranged to project upward through this passage, one of its sides being substantially parallel with the guide-bar *D* and at a sufficient distance therefrom to admit a properly-arranged clasp in the channel-way between

the two. Hence, as the clasps pass down the feed-plate in contact with the guide-bar D, such as have been properly arranged enter readily the channel-way between the point of the needle *m* and the guide-bar D, while the bulk of the misarranged clasps are directed away from the guide-bar by the point of the needle and pass through the escape-slot *f* to the spout G leading to the catch-box H. Occasionally a misarranged clasp may escape the action of the needle, but this is a rare exception to the general rule.

In order that the misarranged clasps may not pass through the passage between the side bar, C, and guide-bar D and fall to the floor, a gate, *h*, is applied to this passage. This gate crosses the passage at an angle, so as to direct such clasps as pass over the needle *m* into the escape-slot *f*, but it has an opening, *e*,

opposite the channel-way, between the needle *m* and guide-bar D, to permit the properly-arranged clasps to pass through to the clasp-supplying device E.

What I claim as my invention, and desire to secure by Letters Patent, is—

1. The combination of the feeding-plate of the hoop-clasping machine and needle, substantially as set forth.

2. The combination of the feeding-plate of the hoop-clasping machine and gate, substantially as set forth.

In witness whereof I have hereunto set my hand this 27th day of April, 1865.

CHAUNCEY L. OLMSTEAD.
